UNITED STATES PATENT OFFICE.

ALBERT PECORELLA, OF BUFFALO, NEW YORK.

TOE-Straightening Device.

1,098,397.

Specification of Letters Patent.

Patented June 2, 1914.

Application filed November 21, 1913. Serial No. 802,242.

To all whom it may concern:

Be it known that I, ALBERT PECORELLA, a citizen of Italy, residing at Buffalo, in the county of Erie and State of New York, have invented new and useful Improvements in Toe-Straightening Devices, of which the following is a specification.

This invention relates to a device for straightening the toes of a foot which tend to grow crooked or lap one over the other, thereby not only interfering with the proper walking of the person but also affecting the comfort and health of the same.

It is the object of this invention to provide a device for this purpose which can be applied to the foot and toes in such manner as will permit of wearing the usual shoe and which will in due time straighten one or more toes so that they will not overlap one another but lie side by side in proper position relatively to each other.

In the accompanying drawings: Figure 1 is a perspective view showing my invention embodied in a device which is designed to straighten all five toes of a foot. Figs. 2 and 3 are vertical transverse sections taken in the correspondingly numbered lines in Fig. 1. Fig. 4 is a perspective view showing my invention embodied in a device which is designed to straighten only two toes.

Similar characters of reference indicate corresponding parts throughout the several views.

The construction of the toe straightening device shown in Figs. 1-3, is designed to hold all five toes of the foot in a properly straightened position. The device shown in these figures comprises a base, bottom or supporting plate 1 which has its front edge scalloped, as shown at 2, to conform to the five toes which are adapted to rest upon the same while the rear part of this plate is adapted to support the underside of the foot in rear of the toes. At its opposite longitudinal edges the plate is provided with two upwardly turned or curved flanges 3, 4, which are adapted to bear, respectively, against the outer sides of the great toe and the small toe of the foot. Adjacent to the outer sides of the spaces which receive the great and small toes the supporting plate is provided with two front single openings 5, 6 and between the spaces for adjacent toes the plate is provided with pairs of openings 7, four of such pairs being shown in the toe straightening device designed to hold all

five of the toes in place. Adjacent to opposite corners of the rear end of the supporting plate the same is provided with two rear single openings 8, 8.

The retaining plate and the foot are secured to each other by means of a fastening band or ribbon comprising a plurality of loops 9, 10, 11, 12, 13 arranged in a transverse row above the front part of the plate and each adapted to engage with the top and sides of one of the toes, two intermediate portions 14, 14 crossing each other on the underside of the plate and two tying ends 15, 15 adapted to engage with the upper side of the foot in rear of the toes. The outer ends of the outermost loops 9, 13 which embrace the great and small toes pass downwardly through the front single openings 5, 6 and connect with the front ends of the intermediate band portions. The opposing inner ends of two adjacent loops pass downwardly through the members of one pair of intermediate openings 7, and are connected with each other on the underside of the supporting plate. The rear ends of the intermediate band portions pass through the rear single openings 8, 8 and connect with the tying ends of the band.

In applying this device to a foot of a person the tying ends are left loose and the loops in a loose condition are slipped over the several toes of the foot while the same rests upon the plate. The fastening band is then drawn so that the loops are tightened upon the several toes and the latter are separated from each other and held in a proper position side by side and then the tying ends are tied together over the foot in rear of the toes. A stocking may now be drawn over the foot and a shoe worn over the stocking in the usual manner. After thus applying the toe straightening device to the foot a person may walk in shoes without discomfort and without liability of the toe crossing or one overlapping the other. In time therefore the toes will be trained to remain naturally in their normal position and permit of dispensing with the use of this toe straightening device, thereby promoting the health and comfort of persons who have been thus afflicted.

When all five toes of the foot do not require straightening this device may be constructed to apply to only such toes as require straightening. For instance, in Fig. 4 a construction is shown which is designed

to straighten only two toes viz. the great toe and the second toe. In such a construction the supporting plate 16 is made comparatively narrow and the fastening band is only provided with two loops 17, 18 for engagement with the great and second toe, the inner opposing ends of these two loops passing through the members of a pair of adjacent openings 19 while their outer ends pass through single front openings 20, 21 in the plate and connect with the front ends of the crossed intermediate portions 22 of the band and the rear ends of the latter pass through two rear single openings 23 in the plate and connect with the tying ends 24 of the band. When the toe straightening device is thus organized for the great toe and the second toe the supporting plate is provided only with a longitudinal flange 25 adjacent to the great toe but the flange on the longitudinal edge adjacent to the second toe is omitted.

This toe straightening device is comparatively simple in construction and can be produced at comparatively small cost of any suitable material. For instance, the plate may be constructed of sheet metal, such as aluminum or German silver, and the fastening band may be constructed of silk, leather or the like. The upper side of the plate may also be provided with a covering of leather or other soft material to prevent the foot resting on the plate from getting cold.

It will be manifest that this toe straightening device can be very quickly and conveniently applied to and removed from the foot and that the same can be also easily cleaned when necessary, thereby rendering the same very sanitary and in no wise objectionable.

I claim as my invention:

1. A toe straightening device comprising a plate adapted to engage the underside of the foot and the underside of at least two toes and provided adjacent to the outer side of said toes with single openings and be-

tween the opposing inner sides of the adjacent toes with a pair of openings, and a single fastening band provided above the plate with a plurality of loops each of which is adapted to engage the top and sides of a toe, the adjacent inner ends of two loops passing through the members of a pair of openings and connected with each other underneath the plate, and the outer ends of two loops passing through the single openings, respectively of said plate.

2. A toe straightening device comprising a plate adapted to engage with the underside of the foot and the toes and provided at its opposite longitudinal edges with upwardly turned flanges adapted to engage with the outer sides of the great and small toes and also provided with front single openings adjacent to the outer sides of the great and small toe spaces, pairs of openings between adjacent toe spaces and rear single openings adjacent to the outer sides of the foot space, and a fastening band having a plurality of loops above the toe spaces and each adapted to engage with the top and sides of a toe, two intermediate portions which cross each other underneath said plate, and two tying ends which are adapted to engage with the upper side of the foot, the outer ends of the outermost loops passing through said front single openings and connecting respectively with the front ends of said crossed portions, the opposing inner ends of two adjacent loops passing through one of said pairs of openings and connecting with each other underneath said plate, and the rear ends of said crossed portions passing through said rear openings and connecting with said tying ends.

Witness my hand this 17th day of November, 1913.

ALBERT PECORELLA.
